UNITED STATES PATENT OFFICE.

WALTER P. HANSELL, OF PITTSBURG, PENNSYLVANIA.

DESIGN FOR A SOAP-BOX.

SPECIFICATION forming part of Design No. 17,057, dated January 11, 1887.

Application filed October 12, 1886. Serial No. 216,074. Term of patent 14 years.

To all whom it may concern:

Be it known that I, WALTER P. HANSELL, a citizen of the United States, residing at Pittsburgh, in the county of Allegheny and State 5 of Pennsylvania, have invented and produced a new and original Design for a Soap-Box, of which the following is a specification, reference being had to the accompanying drawings, forming part thereof, and which represent, 10 in—

Figure 1, in elevation, a soap-box made according to my design; Fig. 2, a vertical longitudinal section of the same, and Fig. 3 a cross-section thereof.

15 The box consists of a long tube or case, *a*, of any suitable size, closed at each end with a cap, *b*, of the shape of an acorn, and between these acorn-caps a lower case part, *c*, is placed, having a cover in one side. These case parts 20 may be made of any suitable material, and each part is provided with ornamentations consisting of stripes and figures of contrasting colors, which are alternately arranged—first one color, and the next a different color, and 25 so on. The ornamentations on the tubular case part are of the form and style of oblique or spiral stripes, while those on the sides of

the lower case part are of the form and style of diamonds arranged in parallel lines of contrasting colors. The tubular case part *a* is of 30 cylindrical shape in cross-section, and supplements the case part *c*, which is of rectangular shape. These two case parts form a double box, each part forming a separate closure.

35 I claim—

1. The design for a soap-box herein shown and described, the same consisting of the case *a*, capped at each end with an acorn-shaped cover, *b*, and having between said acorn-shaped caps a lower case part, *c*, having a side cover, 40 the said case parts being provided with stripes and figures of contrasting colors alternating with each other.

2. The design for a soap-box herein shown and described, the same consisting of the case 45 *a*, capped at each end with an acorn-shaped cover, *b*, said case part having oblique stripes of contrasting colors alternating with each other.

WALTER P. HANSELL.
